UNITED STATES PATENT OFFICE.

GUSTAV ADOLPH HUBER, OF NEW YORK, N. Y.

ELECTRICAL DEVICE.

1,234,337.

Specification of Letters Patent. Patented July 24, 1917.

Application filed July 18, 1912. Serial No. 710,218.

To all whom it may concern:

Be it known that I, GUSTAV ADOLPH HUBER, a citizen of the United States, residing at the borough of Manhattan, in the county of New York and State of New York, have invented certain new and useful Improvements in Electrical Devices, of which the following is a specification, reference being had therein to the accompanying drawing.

My invention relates to improvements in electric bells, buzzers and similar devices and has especial reference to a combination bell and buzzer.

According to my invention the bell and buzzer are formed upon a single frame and are actuated by the same magnet and either can be operated from any usual distance upon a three wire system.

Referring to the accompanying drawing it will be observed that the frame 2 is provided with three binding posts 3—4—5 to which are connected the three wires of the system 6, 7 and 8 respectively. 9 indicates a suitable battery for supplying the necessary current. 10 is an armature secured upon the usual spring 11 in any usual manner and provided with the hammer 12. 13 is a similar armature without any hammer secured upon the usual spring such as 11'. These springs are mounted upon the pivot 14 suitably secured to the frame 2 as shown. 15 is a suitable core of the frame upon which is wound coils of wire such as 16 thus magnetizing the frame of the bell when the current is on. So far as concerns many aspects of the invention, the body portion of the frame may be of any form, but in accordance with one feature of the invention said

frame has a circular body portion concentric with the core as shown. In operation when the button 17 is pressed the current flows from one terminal 18 of the battery 9, through the wire 7, the insulated terminal 4, wire 19, to the insulated metallic bracket 20 which carries the contact point 21 against which the insulated spring contact 22 normally rests. From the point 22 the wire 23 carries the current to the insulated metallic bracket 20' from which the current passes through the wire 21' into the coil 16 back to the insulated binding post 5 through the connecting wire 24 and from there to the other terminal 25 of the battery 9 by the connecting wire 8.

When the button 26 is pressed, the cur-

rent flows from terminal 18 of the battery 9, through the line 6, the ground binding post 3 and frame 2 of the bell, into the spring 11 which is normally in contact with the connecting point of the metallic bracket 20' from which the current passes through the wire 21', coil 16, and connecting wire 24 to the line 8 and terminal 25 of the battery 9.

From this it will be seen that when the button 26 is pressed, the bell 27 will be rung by the hammer 12, the buzzer also operating, but in a practically unnoticeable and unobjectionable manner, and that when the button 17 is pressed, the buzzer only will be actuated. By this arrangement the structure of a single vibrating bell may be employed and the only attachment necessary for the buzzer is the additional armature and spring 13—11' together with its bracket 20 and their connections. It will further be observed that by this method the three wire circuit 6—7—8 reduces the amount of wiring necessary and thus eliminates another item of expense in the installation of separate bells and buzzers.

It will be understood that changes may be made from the precise structure shown and described, within the scope of the accompanying claims, without departing from the spirit of the invention and without sacrificing its chief advantages.

I claim:

1. An electric alarm including in combination a plate of magnetizable metal, a core connected thereto and provided with a winding, an insulated circuit branch from said winding to one pole of a source of electric energy, two armatures actuated by said plate, two brackets, one for each of said armatures insulated from said plate, an insulated circuit connection from said winding to one of said brackets, an insulated circuit connection from the other of said brackets to the other pole of said source of electric energy, a circuit connection from said magnetizable plate to said last mentioned pole of the source of electrical energy, an insulated electrical connection between said brackets and means for opening and closing said circuits.

2. An electric alarm including in combination a plate of magnetizable metal, a magnet core connected perpendicularly thereto and therebeneath, said plate forming a head and a cover for the magnet, two armatures

- coöperating with said magnet head, plate, make and break mechanisms for each of said armatures, respectively, comprising brackets mounted upon but insulated from said plate, 5 a connection from the magnet winding to one of said brackets, an electrical connection from said last-mentioned bracket through the other make and break mechanism to one pole of a battery, and a connection from the 10 other terminal of the magnet winding to the other pole of said battery.
3. An electric alarm including in combination a plate of magnetizable metal, a magnet core connected perpendicularly thereto and therebeneath, said plate forming a head and a cover for the magnet and having an extension carrying a plurality of binding posts, two armatures coöperating with said magnet head plate, make and break mechanisms for each of said armatures, respectively, comprising brackets mounted upon but insulated from said plate, a connection from the magnet winding to one of said brackets, an electrical connection from said 15 last-mentioned bracket through the other make and break mechanism to one pole of a battery, and a connection from the other terminal of the magnet winding to the other pole of said battery.
- 20 4. An electrical alarm including in combination a plate of magnetizable metal, a magnet core connected perpendicularly thereto and therebeneath, said plate forming a head and a cover for the magnet, two armatures coöperating with said magnet head plate, and electrically connected thereto, make and break mechanisms for each of said armatures, respectively, comprising brackets mounted upon but insulated from said plate, 25 a connection from the magnet winding to the other pole of said battery.
- 30 5. An electrical alarm including in combination a plate of magnetizable metal, a magnet core connected perpendicularly thereto and therebeneath, said plate forming a head and a cover for the magnet, two armatures coöperating with said magnet head plate, and electrically connected thereto, make and break mechanisms for each of said armatures, respectively, comprising brackets mounted upon but insulated from said plate, 35 a connection from the magnet winding to the other pole of said battery.
- 40

one of said brackets, an electrical connection from said last-mentioned bracket through the other make and break mechanism to one pole of a battery, and a connection from the other terminal of the magnet winding to the 45 other pole of said battery.

5. An electrical alarm including in combination a plate of magnetizable metal, a magnet core connected thereto, said plate forming a head for the magnet, two armatures 50 coöperating with said magnet head plate, make and break mechanisms for each of said armatures, respectively, comprising brackets mounted upon but insulated from said plate, a connection from the magnet winding to one of said brackets, an electrical connection from said last-mentioned bracket through the other make and break mechanism to one pole of a battery, and a connection from the 55 other terminal of the magnet winding to the other pole of said battery.

6. An electric alarm including in combination a plate of magnetizable metal constituting a magnet head, a core connected thereto and a winding therefor, two armatures and make and break mechanisms coöperating with said magnetizable head, a bell, a bell clapper carried by one of said armatures, the other of said armatures acting as a buzzer, circuit connections including three branches, with a switch in one branch for the bell and a switch in another branch for the buzzer.

In testimony whereof I affix my signature in presence of two witnesses.

GUSTAV ADOLPH HUBER.
